UNITED STATES PATENT OFFICE.

ALICE M. JONES AND ZELLA GLIMM, OF NEW YORK, N. Y.

ABDOMINAL BAND AND HOSE-SUPPORTER.

1,262,804.

Specification of Letters Patent. Patented Apr. 16, 1918.

Application filed May 19, 1916. Serial No. 98,481.

To all whom it may concern:

Be it known that we, ALICE M. JONES and ZELLA GLIMM, are citizens of the United States, residing at New York, in the county 5 of New York and State of New York, have invented certain new and useful Improvements in Abdominal Bands and Hose-Supporters, of which the following is a full, clear, and exact description, such as will enable others skilled in the art to which it 10 pertains to make and use the same.

This invention relates to an abdominal lifting and supporting band which is anchored in position on the body of the wearer, 15 and with respect to its more specific features, to a combination binder band and hose supporter for children.

One of the objects of the invention is the provision of an efficient device of the character above referred to designed to cause the 20 growing child to assume an erect posture with a relatively flat back and abdomen.

Another object of the invention is the provision of a practical supporter of the character referred to which may be easily put on and taken off and will not deleteriously interfere with the movements of the 25 wearer.

Other objects will be in part obvious and 30 in part pointed out hereinafter.

In the accompanying drawing forming part of this specification, and wherein similar reference characters refer to similar parts throughout the several views—

35 Figure 1 is a view of an embodiment of the invention when lying flat and removed from the body of the wearer;

Fig. 2 is a view illustrating the device as applied to the body of the wearer, looking at 40 the front;

Fig. 3 is a view similar to Fig. 2, looking at the back; and

Fig. 4 is a view similar to Figs. 2 and 3, but looking toward the side of the wearer.

45 In the ordinary forms of children's hose supporters, the pull exerted upon the hose to maintain their proper adjustment is borne by the shoulders of the wearer, the supporters having either shoulder straps or are attached to a waist or the like which hangs 50 from the shoulders. This pull upon the shoulders urges the shoulders forward, causes the shoulder blades to protrude sharply and unnaturally, causes the formation 55 of a sharp, forward bend in the spine near its base, and allows the abdomen to

protrude outwardly and to hang down in a manner very harmful to health, since when the body is so positioned the intestines assume a position in which they are unable to 60 properly perform their functions, and thus severely impairing the health of the person.

It is to overcome the above mentioned objectionable features and others found in the ordinary hose supporters, and to the restraining of the body from assuming such harmful positions that our invention is particularly directed, although other beneficial features are present, as will be pointed out hereafter, 65 and to these ends we have constructed a combined garter and abdominal lifter which is not only free from the above objectionable features, but also is useful in restoring the 70 parts of the body so positioned to their natural, normal and healthful position.

The invention comprises a generally crescentically shaped band of flexible material. The wider portion of the band is adapted 75 to be placed contiguous the hypogastric region of the abdomen and extends therefrom as it narrows in opposite directions about 80 and contiguous the hips and the portion of the body where the small of the back joins the top of the buttocks, at which latter place

the ends are held adjustably together by a 85 buckle carried by one end and in this manner the band is held in its proper encircling position about the body. In this position the portion of the band contiguous the abdomen bears upwardly and inwardly 90 against it and by binding it in place acts as a binder to prevent the abdomen from falling downwardly or outwardly. The amount of tension and binding effect exerted by the band may be regulated by manipulating the 95 ends of the band in connection with the buckle so as to either increase or decrease the size of the encircling element of the band.

The band is prevented from slipping downward by the natural protrusion of the 100 hips and buttocks of the wearer upon which the band rests, and to restrain upward movement of the binder there are attached two tabs of flexible material, preferably, though not necessarily, elastic, to the band, 105 one at each portion of the band adjacent each hip, in such a way that these tabs extend downwardly therefrom on lines respectively between the median side line of the body and the spinal column, and near 110 the lower ends of these tabs we have attached garter clamps, whereby the tabs may

be fastened to the hose of the wearer and thus anchor the band to the hose to prevent upward movement of the band. These tabs are of the ordinary adjustable form usually found in hose supporters and permit of the regulation of the degree of tension exerted upon the hose and permit their adjustment to various lengths of hose. The point of attachment of these tabs is an important feature of our invention, since by attaching them as above described they serve to anchor the band in place irrespective of the posture assumed by the wearer, thus insuring the proper positioning of the band at all times and preventing the band from shifting with the change of posture of the wearer.

Referring now more specifically to the drawings, 1 represents the binder band of flexible, preferably inelastic material such as cotton or linen cloth. The band is crescentically shaped, having an upper generally concave edge 2 and a lower convex edge 3. The upper edge has a slight upward swell at the front as at 3'. The numeral 4 indicates one end portion of the band and 5 represents a buckle attached to the band near its other end, as at 6, leaving an end portion 7 free to be interposed between the buckle and the skin of the wearer to prevent irritation or chafing. The buckle is adapted to be adjustably fastened onto the end portion 4 to hold the band in proper encircling position about the body of the wearer. 8 indicates the wider portion of the band which is to be worn contiguous the hypogastric portion of the abdomen, so that when the band is in position the abdomen will be lifted and supported, as shown in Figs. 2 and 4, the remaining portions of the band extending therefrom in opposite directions adjacent to and resting upon the hips, and the top of the buttocks of the wearer, as shown in Figs. 2, 3, and 4. 9 and 10 are anchoring members, or tabs, attached to the band at points 11 and 12, which points are adjacent the hips of the wearer and these tabs are adapted to hang downwardly therefrom along the sides of the thighs on lines respectively between the median side lines of the body and the spinal column, as before described and as shown in Figs. 3 and 4. Near the lower end of each tab, we have attached garter clasps 13 and 14 of ordinary form, which clasps are adapted to fasten onto the hose of the wearer, as shown in Figs. 3 and 4 to anchor the band against upward movement.

The device is put on in the following manner: The band is grasped by the hand and the central or wider portion is placed

contiguous the hypogastric portion of the abdomen, and the remaining portions of the band are then wound about the body in opposite directions over the tops of the hips and buttocks until the ends meet at the back. The end not carrying the buckle is then inserted into the buckle and pulled until the desired upward and inward binding tension of the band against the abdomen is obtained, whereupon this end is fastened into the buckle. Then each tab is adjusted to the desired length and is fastened onto the hose at such points as will effect the desired anchoring of the belt against upward movement, and at the same time effect the proper positioning of the hose. These adjustments may be made at any time without it being necessary to remove or otherwise manipulate the device, and to take off the device the operations described for putting it on are executed in reverse order.

Thus by the above described construction are accomplished, among others, all of the objects hereinbefore referred to.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

It is also to be understood that the language used in the following claim is intended to cover all of the generic and specific features of the invention herein described, and all statements of the scope of the invention which, as a matter of language, might be said to fall therebetween.

Having described our invention, what we claim as new and desire to secure by Letters Patent is:

A combined garter and abdominal lifter for children, comprising a flexible band adapted to be worn around the body and to lift and support the abdomen, and two pendent anchoring members connected to said band and extending therefrom on lines respectively between the median side line of the body and the spinal column and adapted to be connected to the hose, said pendent members providing the sole hose supporting connection from said band.

In testimony whereof we affix our signatures in the presence of two witnesses.

ALICE M. JONES.
ZELIA GLIMM.
